UNITED STATES PATENT OFFICE.

JOSEPH MORTON, OF LINDON, UTAH.

SLIDING-JAW WRENCH.

No. 853,369.

Specification of Letters Patent.

Patented May 14, 1907.

Application filed September 12, 1906. Serial No. 334,259.

To all whom it may concern:

Be it known that I, JOSEPH MORTON, a citizen of the United States, residing at Lindon, county of Utah, and State of Utah, have invented certain new and useful Improvements in Sliding-Jaw Wrenches, of which the following is a specification.

My invention relates to sliding jaw wrenches of the type having an interrupted screw adapted to engage interrupted screw threads on the sliding jaw.

The object of the present invention is the provision of a wrench of the type specified, in which provision is made for rapid and easy disengagement of the threads of the adjusting screw and those of the sliding jaw, without necessitating careful observation by the user, so that the sliding jaw can be readily adjusted to approximately the desired position and, thereafter a fine adjustment obtained by turning the screw into engagement with the threads on the sliding jaw.

Another object of the invention is the provision of a wrench of the type set forth which will be composed of few parts, durable, strong, and not liable to become damaged or get out of order.

In carrying out the invention, I provide the sliding jaw with an open side communicating with the socket which is adapted to receive the adjusting screw and provide one wall of the socket with interrupted screw threads, the balance being blank, and in connection therewith employ an adjusting screw which has interrupted screw threads to engage those on the sliding jaw, but these screw threads are of less width than the open side in the sliding jaw so that by turning the adjusting screw to bring the interrupted screw threads thereof in alinement with the open side in the sliding jaw, the sliding jaw can be quickly slid to any desired position, and upon re-engagement of the adjusting screw with the threads on the sliding jaw, a fine adjustment of the sliding jaw may be quickly obtained. The formation of the interrupted screw threads on the adjusting screw and their relation to the open side in the sliding jaw gives, in effect, an indicator which at once enables the user to bring the parts to the desired position for rapid sliding of the jaw to approximately the desired position and dispenses with the necessity of employing any kind of a stop or limiting device on the adjusting screw, such as heretofore have been generally employed. The adjusting screw has screw threads to en-

gage with a lug on the wrench and its construction is such that it may be readily removed at any time.

In the accompanying drawings: Figure 1 is 60 a side elevation with a part of the wrench in section; Fig. 2, an edge view, partly in section; Fig. 3, a cross-section on line 3—3 of Fig. 1, but showing the adjusting screw turned so that the interrupted screw threads 65 thereon are in alinement with the open side in the sliding jaw; and Fig. 4, a detail perspective of the sliding jaw with parts broken away to better illustrate the interrupted screw threads. 70

To the usual handle 1 is secured the guide-bar 2, which has the fixed jaw 3. Attached to the guide-bar 2 is an arm or lug 4 which has internal screw threads at 5.

The sliding jaw is shown at 6, the same 75 having a socket 7 which is cylindrical and perfectly smooth, except at one side where it is provided with interrupted and depressed screw threads 8. The sliding jaw has an open side 9 which communicates with the socket 80 7 the entire length thereof.

The adjusting screw 10 has a screw threaded part 11 to engage the screw threads 5 and its stem 12 is of less diameter than the screw threaded opening 5 and perfectly smooth and cylindrical throughout its length and of a size to fit the socket 7, except that along one part thereof it is provided with the interrupted screw threads 13 corresponding to the screw-threaded part 8. The screw-threads 90 13 are, as shown in Fig. 3, of less width than the open side 9 so that when the screw is turned to bring the threads 13 into the open side, the sliding jaw can be freely slid along the guide-bar 2. 95

In operation, the thumb-piece 10^a is turned with the fingers to bring the threads 13 into the open side 9 and the sliding jaw 6 is then slid along to the desired position and thereafter the adjusting screw is turned to cause the screw threads 13 to engage the screw threads 8 and a fine adjustment of the sliding jaw can then be obtained. 100

On account of the stem of the adjusting screw being of less size than the screw-threaded opening 5, the adjusting screw can be removed through the opening 5, when desired. 105

The screw-threads 13, in connection with the open side 9, constitute an indicating 110 means by which the user can, without careful observation, at once position the parts so

that the sliding jaw may be rapidly slid on the guide-bar, and this construction also obviates the necessity of using limiting or stop lugs of any kind on the adjusting screw.

Having thus described my invention, what I claim as new and desire to secure by Letters Patent, is:

1. In a wrench, the combination with a guide-bar, of a sliding jaw having a socket provided with interrupted screw-threads and with an open side extending lengthwise of the sliding jaw and guidebar, and an adjusting screw received in the socket and provided with interrupted screw-threads adapted to be brought into alinement with the aforesaid open side or engaged with the screw-threads of the sliding jaw.

2. In a wrench, the combination with a guide-bar and an arm or lug having a screw-threaded opening, of a sliding jaw movable

on the guide-bar and provided with a socket which has interrupted screw-threads and is provided with an open side communicating therewith and extending lengthwise thereof, an adjusting screw having a screw-threaded part engaged with the screw-threaded opening in the lug and provided with a shank or stem received in the socket of the sliding jaw and provided with interrupted screw-threads of less width than the open side and adapted to be brought into alinement with the open side or made to engage the interrupted screw-threads of the sliding jaw.

In testimony whereof, I hereunto affix my signature in presence of two witnesses.

JOSEPH MORTON.
